UNITED STATES PATENT OFFICE.

JOHN J. ZNAK, OF BROUGHTON, PENNSYLVANIA.

RAIL JOINT.

1,414,450.

Specification of Letters Patent.

Patented May 2, 1922.

Application filed February 4, 1922. Serial No. 534,075.

To all whom it may concern:

Be it known that I, JOHN J. ZNAK, a citizen of the United States, residing at Broughton, in the county of Allegheny and State of Pennsylvania, have invented certain new and useful Improvements in Rail Joints, of which the following is a specification, reference being had to the accompanying drawings.

10 This invention relates to rail joints and has for an important object thereof the provision of a rail joint whereby the abutting ends of rails may be connected without the use of bolts and the like.

15 An important object of the invention is to provide an improved device of this character which may be very cheaply produced and which is readily applied to the rails.

These and other objects I attain by the 20 construction and arrangement shown in the accompanying drawings wherein for the purpose of illustration is shown a preferred embodiment of my invention and wherein like reference characters designate like parts 25 throughout.

In the drawings:

Figure 1 is a perspective view of a rail joint constructed in accordance with my invention;

30 Figure 2 is a section on the line 2—2 of Figure 1; and

Figure 3 is a section on the line 3—3 of Figure 1.

Referring now more particularly to the 35 drawings, the numeral 10 indicates a plate adapted to be arranged upon a tie and provided upon the outer surface thereof with upstanding lugs 11, the lugs 11 being arranged in spaced rows and being preferably 40 uniformly spaced. The adjoining ends of the rail sections R and R' are provided in the flanges F of the base thereof with openings 11^a through which the lugs 11 extend, the lugs 11 being of greater length than the 45 thickness of the base flanges.

The numeral 12 designates fish plates, one 50 of which is adapted to be arranged upon each side of the rail which has its inner or rail engaging face adapted to conform to the shaping of the rail so that it abuts beneath the shoulder S of the rail head H against the web W and against the flange F. The plates 12 are of such thickness that they overhang the openings 11^a of the base flanges

and the plates are provided with notches 13 55 aligning with these openings.

In the use of my device the fish plates are applied to the opposite sides of the adjoining rail ends and the lugs of the plate 10 forced through the openings of the rail 60 flanges and into the sockets of the fish plates. These lugs being rigid, will maintain the fish plates in engagement against the sides of the rail webs preventing side play of the 65 rails, and the engagement of the lugs in the rail openings 11^a will prevent longitudinal shifting or side play of the rail at the base thereof. The plates 10 are preferably of greater width than the base of the rail and are provided in the sides thereof with openings 14 through which retaining spikes 15 70 may be engaged to secure the rails to the tie T.

From the foregoing it is believed to be 75 obvious that a rail joint constructed in accordance with my invention is particularly well adapted to the use for which it is intended by reason of the fact that it may be readily and cheaply constructed and applied and by reason of the fact that it eliminates 80 the necessity of using bolts in securing the fish plates. It will furthermore be obvious that the construction thereof as hereinbefore set forth is capable of some change and modification without materially departing from 85 the spirit of my invention and I accordingly do not limit myself to the specific structure thereof except as hereinafter claimed.

What I claim is:

In a rail joint, the combination with adjoining ends of rails having openings formed 90 through the base flanges thereof in spaced relation to the rail web, of fish plates abutting the side faces of the web of adjoining ends of the rails and provided in their outer faces 95 with notches coinciding with the openings of the base flanges of the rail, and a plate arranged beneath the rails and embodying integral lugs extending through the openings of the base flanges and engaging in said 100 notches, said plate being of greater width than the rail base and being provided with openings through which retaining elements may be extended for engagement with a tie.

In testimony whereof I hereunto affix my 105 signature.

JOHN J. ZNAK.
